INVENTOR:
ARTHUR R. NEEF
BY *Jaydon T. Jaydon*
ATTORNEYS.

UNITED STATES PATENT OFFICE.

ARTHUR R. NEEF, OF ST. LOUIS, MISSOURI.

PROTECTING ATTACHMENT FOR REPEATING GUNS.

Application filed October 1, 1925. Serial No. 59,809.

My invention consists in the novel construction, combination and arrangement of parts hereinafter particularly described and distinctly claimed.

5 The object of my invention is to provide a protecting attachment for repeating guns commonly known as repeating shotguns, and which device will be very efficient in its purpose of preventing sand, dirt, grit and other 10 small particles of like nature from entering the delicate working mechanism that is common in the manufacture of guns of this nature, while the hunter is using his gun on sand-bars, in pits, blinds or other such 15 places as are used by hunters when hunting wild ducks or other wild game.

It is well-known to hunters of wild ducks or other wild game, that while on a sand-bar, or in a pit or blind, waiting for a flock 20 of wild ducks or other game, to fly over or land near enough to get a good shot, the hunter will lay his gun against the bank of the pit, the barrel pointing upward, and that the wind, or other such disturbances 25 have caused the sand to fall into the working mechanism of the gun, causing said gun to choke up and become inoperable, and also causing the hunter to lose many a good shot, making it necessary to disjoint the 30 gun, clean out the sand, and re-assemble the said gun before being able to use it again, causing much loss of time, and often ruining the day for the hunter.

A further object of my invention is to 35 provide an attachment of the character described that will be simple in construction, easy to be assembled, durable in operation and of very low cost to manufacture.

In the drawings:

40 Fig. 1 is a sectional side elevation of my invention as it appears when in use on a gun known as a repeating pump shotgun, parts being broken away to show several of the working parts on the interior thereof.

45 Fig. 2 is a top plan-view of my invention assembled, and as it appears before being put into position on a gun, parts being broken away to show several of the working parts on the interior thereof.

50 Fig. 3 is a section of one of the set-collars, the section being taken on the line 3—3 of Fig. 1.

Fig. 4 is a section taken on the line 4—4 of Fig. 1.

Fig. 5 is a section of the rear portion of 55 the invention, the section being taken on the line 5—5 of Fig. 1.

Fig. 6 is a section of another view of the set-collar mentioned above, the section being taken on the line 6—6 of Fig. 2. 60

Fig. 7 is a section of a set-collar that is secured to the receiver or breech of the gun, the section being taken on the line 7—7 of Fig. 2.

Fig. 8 is an inverted top-plan view of a 65 trap-door that is removed from the bottom portion of the rear casing when the gun is to be loaded.

Fig. 9 is a top plan-view of a spring that is used in the construction of my invention. 70

Fig. 10 is an end view of a sight adapter, and

Fig. 11 is a section taken on the line 11—11 of Fig. 2.

Referring now to the accompanying drawings in which I have shown the preferred embodiment of my invention, which will now be described, the numeral 1 designates a sheet metal-casing that is oblong in shape, and which is provided with a series of U-shaped slots 2 at one of its ends, and adapted to receive a series of screws 3 that are screwed into a flanged set-collar 4 which is clamped around the receiver or breech 5 of the gun. 75

Said casing 1 is also provided with a longitudinal slot 6 through which is inserted to slide longitudinally therein, a handle 7 that is screwed into a metal fore-end 8 which has been secured in place on the magazine 90 chamber 9 of the gun, in place of the original wood fore-end which is placed on said gun when manufactured.

I have found it necessary to remove the 95 said wood fore-end from the gun, and replace it with a metal fore-end 8, because of the fact that said wood fore-end is of insufficient thickness to permit the drilling and tapping of a hole that is necessary to permit the reception of the screw-threaded end of a bolt 10 upon which the said handle 7 is mounted.

The said metal fore-end may be made of 100 any suitable light metal, preferably of aluminum, and it is held in position on the said magazine chamber by means of the usual collar 11.

The numeral 12 designates a metal slide

that is provided at about the center of its length, with a hole or perforation through which is inserted the said screw-threaded end of the said bolt 10.

5 The numeral 13 designates spring-clips that are secured in any well-known manner to the said slide 12, and are adapted to receive the free ends of a spring 14 which is also provided at about the center of its 10 length, with a hole or perforation through which is passed the said screw-threaded end of the said bolt 10.

The said metal slide 13 and the said spring 14 are placed in position on the said bolt 10 after the latter has been inserted through 15 the said longitudinal slot 6 in the said casing 1.

The said bolt 10 is then screwed into the 20 said screw-threaded hole in the said metal fore-end 8, and the pressure of the said spring 14 coming into contact with the underside of the said fore-end 8 causes the 25 said metal slide to bear against the interior walls of the said longitudinal slot 6, making a tight cover for the said slot and at the same time preventing sand, dirt, grit or other small particles from entering the working mechanism of the gun.

The numeral 15 designates a flanged set- 30 collar that is preferably made in two sections, the sections being so shaped as to fit snugly around the outer periphery of the gun-barrel and the magazine-chamber, the said sections being held together in a 35 clamped position on the said gun-barrel and magazine-chamber by means of screws 16 and 17 entering into screw-threaded holes that are formed in the ends of a grip-pin 18; said pin being constructed so as to fit 40 in the space between the said gun-barrel and the magazine-chamber of the gun.

The free end of the said casing 1 is then slipped under the flanged portion of the said 45 flanged set-collar 15, and the latter is forced against the edge of the said casing 1 and is tightened in position by tightening the said screws 16 and 17, thus holding the casing 1 in its proper position on the gun.

The numeral 19 designates a large rear 50 casing that is provided with a series of U-shaped slots 20 that are adapted to receive a series of screws 21 that are screwed into the said flanged set-collar 4.

The numeral 22 designates a large U- 55 shaped slot that is cut in the top portion of the casing 19, at the free end thereof, and directly above the hammer of the gun; the edges of the said slot being beveled so as to receive the beveled edges of a slide or cover 23, the latter being provided with lugs 60 65 24 that are secured to the underside thereof, and adapted to engage the interior wall of the said casing 19, thus holding the said slide or cover into contact with the said casing 19.

The said slide or cover 23 acts as a shield to prevent sand or other small particles of dirt from entering the working mechanism of the gun, and also acts as a guard for the hammer of the gun, preventing the hunter 70 from accidentally catching the hammer of his gun on a barbed-wire fence while crawling through or between the barbed wires of the fence while hunting.

The said slide or cover 23 may be quickly 75 removed from the said casing 19, should the hunter find it necessary to quickly cock the hammer of his gun in order to make a quick shot, or if it be necessary for the hunter to un-cock his gun without discharging the shell in the breech of the gun.

The numeral 25 designates a sort of a trap-door that is provided with latching-lugs 26 and 27 that are connected to, and are operated by, arms 28 and 29, said arms 85 being pivotally connected to the opposite sides of a disk 30 which is secured to a knob 31, the turning of which forces the said latching-lugs outwardly and into contact with the interior wall of said casing 19, said door 25 fitting into a correspondingly shaped hole that is cut in the underside of the said casing 19.

Said door 25 is also provided with a strip 90 of sheet-metal 32 that is bent upwardly therefrom and acts as a partition to prevent the empty shells from falling under the breech of the gun when said shells are ejected after being discharged.

By removing the said door 25 from the 95 said casing 19, the empty shells, designated by the numeral 33 may be removed, and the magazine-chamber reloaded and made ready so as to continue hunting.

The said latching-lugs 26 and 27 are held 100 in position on the door by straps 34 and 35 which are secured to the said door in any well-known manner.

The numeral 36 designates a sight-way 105 that is formed on the upper side of, and in the flange of the said set-collar 4, and when the latter is clamped in position on the receiver or breech of the gun, the said sight-way 36 is directly above the original sight-way, and is directly in line therewith.

The numeral 37 designates a sight adapter 110 that is split at its lower end to permit it to be slipped over the front or muzzle of the gun-barrel, the clamping being accomplished by the tightening of a screw 38 115 which passes through a hole bored in one side of the adapter and engaging the screw-threaded hole in the opposite side thereof.

The said sight adapter is also provided 120 with a recess 39 into which snugly fits the original sight of the gun, thus bringing the bead 40 on the said sight adapter directly in line with the said sight-way 36 that is 125 formed in the said flange of the said set-collar 4.

The said flanged set-collar 4 is split at its lower end to permit it to be clamped around the receiver or breech of the gun, the clamping being accomplished by the tightening of 5 a screw 41 which passes through a hole bored in one side of the set-collar, and engages the screw-threaded hole in the opposite side of said set-collar.

My invention is attached to a gun in the 10 following manner:—

The set-collar 4 is first placed in position on the receiver or breech portion of the gun, while the latter is un-jointed, and is tightened thereon, making certain that the sight-way 15 36 is directly above the original sight-way of the gun.

The rear casing 19 is then placed in position on the set-collar 4 and the screws 21 are tightened against the top edges of the 20 said U-shaped slots 20.

The said casing 1 is then placed in position and the screws 3 are clamped down upon the top edges of the said U-shaped slots 2.

25 The said spring 14 is then placed in position on the metal slide 12 by securing the ends of said spring under the said spring-clips 13, and both the metal slide and the spring are slipped into position on the inside 30 of the casing 1, above the longitudinal slot 6, and the handle containing the bolt 10 is screwed into the metal fore-end 8.

The said flanged set-collar 15 is then placed into position and tightened, holding the said casing 1 in its proper position on the gun.

The said handle 7 is then tightened into the said metal fore-end 8, and the gun is ready for use.

40 I may add that my invention may also be used upon guns known as automatic repeating shot-guns, but of course, many parts of my invention will not be needed and may be eliminated when using said invention on guns of the class above described.

45 While I have illustrated certain details which I deemed to be particularly effective, and have illustrated a construction which is very easy to be assembled, I do not wish to be limited to these details, as it is obvious that many changes may be made therein, without departing from the spirit or scope of my invention.

Having thus described my invention, what

I claim as new and desire to secure by 55 Letters Patent is:—

1. A protecting attachment for repeating guns composed of suitable casings; suitable set collars for securing said casings in position on said gun; a handle carrying a bolt, 60 the latter being adapted to be inserted through a longitudinal slot formed in one of said casings; a metal fore-end mounted upon the magazine chamber of said gun and provided with a screw-threaded hole 65 for the reception of said bolt, and a metal slide for covering said slot in said casing, as and for the purpose set forth.

2. A protecting attachment for repeating guns comprising the elements mentioned in 70 the above claim 1; of suitable spring clips mounted adjacent the ends of said metal slide and adapted to receive the ends of a spring, the latter being provided with a hole through which the said bolt of said handle 75 is inserted and screwed into the said metal fore-end, the pressure of said spring causing the said metal slide to bear against the interior walls of the above mentioned slot in said casing, making a tight cover for the 80 said slot, as and for the purpose set forth.

3. A protecting attachment for repeating guns composed of the elements recited in the above claim 1; of a suitable trap door adapted to be secured to the underside of one 85 of said casings, of latching lugs mounted upon said trap door, and means for forcing said latching lugs into a latching position after said door has been placed in position on said casing, as and for the purpose set forth. 90

4. A protecting attachment for repeating guns composed of the elements recited in the above claim 1; and a sight-way formed on the top plane of one of said flanged set collars, as and for the purpose set forth. 95

5. The combination of a protecting attachment for repeating guns, and a sight adapter carrying a bead, said sight adapter being provided with a recess into which fits snugly the original bead of the gun so that 100 the said bead on the said sight adapter will be directly in line with a sight way formed on the outer edge of one of a pair of flanged set-collars, substantially as described.

In testimony whereof, I have signed my 105 name to this specification.

ARTHUR R. NEEF.
